UNITED STATES PATENT OFFICE.

JOHN C. DUEBER, OF NEWPORT, KENTUCKY.

DESIGN FOR A WATCH-PENDANT.

SPECIFICATION forming part of Design No. 20,202, dated October 14, 1890.

Application filed September 19, 1890. Serial No. 365,564. Term of patent 14 years.

To all whom it may concern:

Be it known that I, JOHN C. DUEBER, a citizen of the United States, and a resident of Newport, county of Campbell, State of Kentucky, have invented a new and useful Design for Watch-Pendants, of which the following is a full, clear, and exact description, reference being had to the accompanying drawings, making part of this specification.

10 My invention relates to a design for watch-pendants.

Figure 1 of the accompanying drawings is a front view of a watch-pendant illustrating my invention; and Fig. 2 is a side view of 15 same, partly sectional, to show the end of the melon-shaped bar.

Similar letters of reference indicate corresponding parts in both of the figures.

The stem portion of the pendant comprises 20 a shoulder portion A, a neck portion B, and a head or end portion C.

The particular feature of my invention to which I now call attention is the grooved or fluted melon-shaped bar D, that connects the head portion of the stem with the neck, as 25 shown, the bow E to take in the ends of the bar D and the crown F to pass over the end of the stem to a point adjacent to bar D.

What I claim as new, and desire to secure by Letters Patent, is—

30 The design for a watch-pendant, as herein shown and set forth.

In testimony whereof I have hereunto set my hand this 6th day of September, A. D. 1890.

JOHN C. DUEBER.
